UNITED STATES PATENT OFFICE.

JAMES WALKER, OF COLUMBUS, OHIO, ASSIGNEE TO SOLAR-STURGES MFG. CO., A CORPORATION OF ILLINOIS.

WASTECAN.

Application filed November 5, 1921. Serial No. 512,983.

To all whom it may concern:

Be it known that I, JAMES WALKER, a citizen of the United States, and a resident of the city of Columbus, in the county of Franklin and State of Ohio, have invented certain new and useful Improvements in a Wastecan; and I do hereby declare that the following is a full, clear, and exact description of the same, reference being had to the accompanying drawings, and to the numerals of reference marked thereon, which form a part of this specification.

This invention relates to a waste can and particularly to a waste can which may be shipped or stored disassembled to effect an economy of space and which may be conveniently and quickly assembled for use.

Waste cans are of necessity of considerable bulk relative to their weight and when it is necessary to ship large numbers of such bulky articles the problem of transportation charges becomes a serious one on account of the higher rates per weight unit charged for the shipment of bulky articles.

It is therefore an object of the present invention to provide a waste can which may be packed in a small space.

It is another object of this invention to provide a receptacle having its various portions joined together by separable connecting means.

It is a further object of this invention to provide a receptacle of the class described having improved interlocking and bracing portions.

It is also an object of this invention to provide a waste can having improved means for suspending a supplemental containing means therein.

It is an important object of this invention to provide a waste can which may be economically constructed and which may be disassembled and packed in a small space.

Other and further important objects of this invention will be apparent from the disclosures in the specification and the accompanying drawings.

The invention (in a preferred form) is illustrated in the drawings and hereinafter more fully described.

On the drawings:

Figure 1 is a side elevation, with parts

in section, of a waste can embodying the principles of this invention.

Figure 2 is a top plan view of the waste can with the cover removed.

Figure 3 is a section on the line 3—3 of Figure 1, with parts omitted.

Figure 4 is an enlarged sectional detail showing a method of securing the cover to the can.

Figure 5 is an enlarged sectional detail showing the method of supporting the supplemental container in position.

As shown on the drawings:

The outside container comprises wall portions 1 which are joined together at their corners by the engagement of angle flanges 2 formed along the edges of one wall between the inner edge of the adjacent wall and guide-ways or offset retaining means 3 which are secured to said inner edges. The edge of the side wall which is provided with the guide-way 3 extends outwardly to a point in line with the outside of the adjacent side wall and is provided with a right angle flange 4 which rests in a depression afforded by the offset portion 5 of said adjacent wall. It will thus be noted that an interlocking joint is formed at the corners of the container along the edges of the adjacent walls, and it is also apparent that this locking joint may be provided at each corner or that certain of the side walls may be made integral and only diagonally opposite corners joined in this manner.

The bottom of the container is braced by a band 6 which abuts the inner side of the walls 1 along the lower edges thereof and which is preferably secured to said walls by means of screws or bolts 7. The upper edges of the walls 1 are braced by rigid members 8 which are secured to the inner sides thereof by spot-welding or other suitable means. The upper edges of the walls 1 are provided with offset portions 10 near the corners thereof and engaged between said offset portions 10 and the bracing members 8 at each corner of the container is a corner bracing member 11 which acts to brace the corners of the container and to aid in securing the side walls more firmly together. Struck downwardly from the horizontal portion of each of said corner bracing mem-

bers 11 is a lug 12, and engaged over each of said lugs is a metallic hook 13 which is engaged through the upper edge of a cloth sack 14 or other flexible supplemental container to support the same in position inside the walls 1. A gable cover 15 is hinged and removably secured on the top of the container by the engagement of pins 16 secured to the under side thereof with hinges 17 which are secured to the outside of one of the walls 1 near the upper edges thereof. Said gable cover 15 is preferably provided with a swinging closure member 18 which is hinged at the top thereof and adapted to be swung outwardly from the cover to permit the deposition of material in the supplemental container or sack 14.

It will be apparent from the foregoing description that this invention provides a container which may be easily shipped in disassembled condition and conveniently assembled in position for use. The various portions comprising the container are preferably constructed of sheet metal and an economical construction is thus afforded. In order to remove the waste material from the container it is only necessary to lift the supplemental container 14 therefrom, after which it may be replaced by a similar supplemental container or emptied and again adjusted in position on the supporting hooks 13. The interlocking joints which are provided at the corners of the side walls afford a rigid construction which is reinforced by the corner bracing means 11, the bottom band 6 and the bracing members 8.

I am aware that numerous details of construction may be varied through a wide range without departing from the principles of this invention, and I therefore do not purpose limiting the patent granted otherwise than necessitated by the prior art.

I claim as my invention:

1. A waste receptacle comprising in combination a plurality of side walls, interlocking means on the adjacent edges of said walls whereby the same may be removably secured together, bracing means secured in-

side the upper ends of the side walls, and corner braces engaged between the inside of the walls and said bracing means.

2. A waste receptacle comprising in combination a plurality of side walls, interlocking means on the adjacent edges of said walls whereby the same may be removably secured together, bracing means inside the upper ends of the side walls, offset portions on the side walls, and corner braces engaged between the insides of said offset portions and said bracing means.

3. A waste receptacle comprising in combination a plurality of side walls, interlocking means on adjacent edges of said walls whereby the same may be removably secured together, bracing means removably engaged inside the upper ends of the side walls, corner braces engaged between the inside of the walls and said bracing means, an integral lug on each corner brace, a hook removably secured to each lug, and a flexible supplemental container supported by said hooks.

4. A waste receptacle comprising in combination a plurality of side wall members having their adjacent side edges so formed and arranged as to be capable of being slid longitudinally into and out of interlocking engagement with each other; a brace extending continuously across the top of each said member and so arranged adjacent its ends as to offer means for the engagement of corner braces; corner braces releasably engaged with said means and serving to brace angularly the adjacent interlocking joint between side wall members; and a polygonal band releasably connected with the side wall members near the bottoms thereof and serving to brace said members angularly and to prevent relative longitudinal movement thereof.

In testimony whereof I have hereunto subscribed my name in the presence of two subscribing witnesses.

JAMES WALKER.
